CANNON

Louis L. Driggs, Jr., Tippecanoe City, Ohio

Application October 24, 1931. Serial No. 570,819

15 Claims. (Cl. 89—43)

My invention relates to cannons.

It is the object of my invention to provide a breech-loading type of cannon adapted for use with fixed ammunition, that is light and simply constructed but easily capable of absorbing the shock of recoil and of transmitting such shock, or as much of it as may be left after absorption, to the foundation upon which the cannon rests.

It is a particular object of my invention to provide means of mounting the barrel of the cannon and its recoil mechanism in such a manner as to readily absorb the recoil, to guide the gun barrel during recoil and return to battery, and to transmit the shock therefrom left over after recoil has been absorbed partially to the foundation upon which the cannon is mounted, and to permit of the adjustment for elevation or for traversing of the gun without impeding the enjoyment of the above mentioned advantages.

20 It is an object to provide a strong durable gun capable of handling relatively large ammunition, which gun, at the same time, is so light in construction that it may be easily handled.

In particular, it is my object to provide a unitary mounting for the recoil mechanism and for guiding the gun during recoil and return to battery.

It is a further object to provide for the mounting of the recoil mechanism which can be readily assembled, disassembled, adjusted and repaired without disturbing the mounting of the gun itself, and to provide for the mounting of a gun which may be adjusted or modified without disturbing the recoil mechanism, while, at the same time, providing a unitary structure for supporting both the gun and the recoil mechanism in requisite parallel relationship.

Referring to the drawings:

Figure 1 is a side elevation of the gun;

40 Figure 2 is a similar view showing the gun and recoil mechanism in longitudinal section;

Figure 3 is an isometric perspective from the breech end of the gun looking at it from the left hand side with the breech block open;

45 Figure 4 is a rear elevation thereof;

Figure 5 is a detail side elevation of the trunnion support for the gun and recoil mechanism cradle which carries the gun sleeve and the recoil sleeve;

50 Figure 6 is a front elevation of the gun showing in section the trunnion support, the foundation support and locking mechanism between the gun cradle supported on the trunnion and the foundation support;

55 Figure 7 is a section on the line 7—7 looking in

the direction of the arrows showing the arrangement of ports in the recoil mechanism piston.

Referring to the drawings in detail, 1 generally designates the foundation support which comprises a unitary U-shaped casting having upwardly extending side arms 2 terminating in trunnion bearing surfaces 3 for receiving the trunnion bearing sleeve 4, which is clamped to it by the trunnion clamp 5 by the bolts 6. These side arms 2 are connected together by transverse members 7 and 8 which are provided with a vertical sleeve 9 for receiving a foundation pin 10, which may be, as in the case of marine work, a part of the towing post of a boat, forming a part of the foundation and on which the cannon 70 rotates as it is traversed. 11 designates generally a cradle having integrally formed thereon on each side the cradle sleeve 4 which is reduced from the maximum diameter of the cradle trunnions 12 to form shoulders 13 abutting on the 75 interior of the upper end of the side arm 2 of the foundation support and the clamp 5, thus limiting lateral movement of the cradle within the foundation supporting arms 2, while, at the same time, permitting of rotation about the axis XX 80 for the adjustment of the cannon in its proper elevation.

In order to hold the cannon in its adjusted position, one of the cradle trunnion sleeves 12 is provided with a depending flange 14 engaged on one side by an abutment 15 riveted to the plate 8 of the foundation support and engaged on the other side by a clamp screw 16 adjusted by the handle 17, which screw is threaded at 18 in the foundation support 1.

The cradle 11 is provided with a lower gun barrel receiving sleeve 19 and with an upper recoil receiving sleeve 20.

The lower gun bearing sleeve carries the guiding sleeve 21 which is restricted at its forward end at 22 and is provided with an annular bearing and sealing sleeve or ring 23 engaging the barrel 24 of the cannon. This sleeve 23 forms a guide at the forward end of the sleeve 21 for the recoil of the cannon and its return to battery.

A rear sleeve or sealing ring 25 forms a bearing in the sleeve 21 for the breech end of the gun and acts as a limiting stop against the shoulder 26 on the cannon to the extent to which the cannon will return to battery, and is provided with a spline 27 operating in the groove 28 of the cannon for guiding the cannon in its reciprocating motion during recoil and return to battery. The barrel 24 has mounted on the breech end a breech block guide casing 29 that carries 110

a transversely reciprocating breech block 30 guided by the grooves 31 and 32 and actuated by the bell crank 33 and handle 34. One end of the bell crank 33 has a cam pin 35 operating in the breech block cam slide 36. 37 designates the firing hammer and 38 the breech block lock. The breech block casing 29 is provided with an up-standing ear 39 which receives the threaded end 40 of the recoil rod 41 to which it is locked by the locking nut 42.

The exact details of the breech block are not of importance in connection with the present invention. They are more fully set forth and claimed in my copending application, Serial No. 15 515,102, filed February 11, 1931.

Turning to the recoil mechanism and its mounting, it will be noted that I have provided a very heavy sleeve 20 formed as a part of the cradle casting which takes the shock of recoil as the recoil cylinder 42a has a shoulder 43 engaging with the forward shoulder 44 of the cradle sleeve 20. The rear end of this sleeve as at 45 is threaded into the rear end of the cradle sleeve 20 against the shoulder which engages the locking nut 46 and this locking nut 46 in turn engages the locking nut 47. The rear end of the sleeve 42 has threaded thereon a packing member 48 with an internally-extending sleeve or cylinder 49 on which is mounted the helical spring 50 that acts as a recoil spring. This sleeve 49 acts as a cylinder through which liquid can be ejected through the side ports 51. On the rod 41 is mounted a piston 52 adapted to be received in such cylinder.

The forward end of the rod 41 is provided with a slotted piston 53 having by-pass ports 54 and 55. The by-pass ports 54 are merely ports or orifices which are never covered by the valve member 56 hereinafter described. These small ports control the movement for return to battery. The spring-loaded valve 56 loaded by the spring 57 is used to control the orifice 55 in the head of the piston 53. This valve can be lifted by the pressure on the left hand side of the piston 53 when the pressure is sufficient to compress the spring 57, one end of which abuts against the supplementary piston and abutment 58 threaded upon the threaded end 59 of the rod 41. The piston works in the supplementary restricted cylinder 62 and acts as a shock absorber.

In operation, the fluid introduced into the cylinder through the port 60 closed by the plug 61 is compressed on the left hand of the cylinder 53 and is restricted in its outlet through the ports 54 and 55. During this movement of recoil the spring 50 is compressed ready for return by the spring of the cannon barrel 24 to battery. This recoil movement is damped at its end by the piston 52 entering the cylinder 49 where liquid is confined and slowly escapes through the ports 51 which act as bleeder ports. This piston and cylinder construction restrain possible over-travel and prevents metal to metal contact in the event of such over-travel. Either of the holes 51 may be employed, or bleeder grooves may be formed in the face of the piston 52.

Upon return to battery under the influence of the spring 50 the return movement is restricted by the small ports 54 which serve to control the movement in returning to battery.

It will be understood that the liquid introduced within the cylinder 42a in the port 60

is preferably oil or a mixture of glycerin and water.

A threaded cover sleeve or supplementary restricted cylinder 62 is provided on the forward end of the cylinder 42 and a packing 63 around the rod 41 at the rear end of the cylinder 42a. 80

When it is desired to adjust or replace this mechanism, all that it is necessary to do is to detach the rod 41 from the ear 39, remove the nuts 46 and 47 and closure 48 thereby sliding the recoil cylinder 42a out of the cradle sleeve 20. 85

It will be understood that I desire to comprehend within my invention such modifications as may be necessary to adapt it to varying conditions and uses. 90

Having thus fully described my invention, what I claim as new and desire to secure by Letters Patent, is:

1. In combination, a cradle having an upper and lower sleeve, a guide sleeve mounted in the lower cradle sleeve, a cannon barrel reciprocal therein, and a bearing sleeve at each end of the guide sleeve for engaging the barrel. 95

2. In combination, a cradle having an upper and lower sleeve, a guide sleeve having a bearing sleeve at each end mounted in the lower cradle sleeve, a cannon barrel reciprocal in the guide sleeve and supported by the bearing sleeves, a recoil cylinder mounted in the upper cradle sleeve, and means supported independent of the upper sleeve to prevent movement of said recoil cylinder in said upper sleeve. 100

3. In combination, a cradle having an upper and lower sleeve, a guide sleeve having a bearing sleeve at each end mounted in the lower cradle sleeve, a cannon barrel reciprocal in the guide sleeve and supported by the bearing sleeves, a recoil cylinder mounted in the upper cradle sleeve, means supported independent of the upper sleeve to prevent movement of said recoil cylinder in 110 said upper sleeve, recoil mechanism in the recoil cylinder extending out of said cylinder, and means connecting said recoil mechanism to said cannon barrel. 115

4. In combination, in a cannon having a barrel and a recoil cylinder, a cradle having a relatively short barrel supporting sleeve in which the barrel reciprocates, a relatively long recoil cylinder sleeve in which a recoil cylinder is held rigidly against movement, a relatively long barrel supporting sleeve in the first mentioned sleeve of the cradle rigidly mounted therein, and a cannon barrel adapted to reciprocate therein. 125

5. In combination, in a cannon, a cradle having a barrel supporting sleeve and a superimposed recoil cylinder supporting sleeve, a guide sleeve for said barrel rigidly mounted in the cannon supporting sleeve of the cradle, bearing sleeves on said guide sleeve for slidably engaging a cannon barrel to form with the barrel a chamber. 135

6. In combination, in a cannon, a cradle having a barrel supporting sleeve and a superimposed recoil cylinder supporting sleeve, a guide sleeve for said barrel rigidly mounted in the cannon supporting sleeve of the cradle, a bearing sleeve 140 on each end of said guide sleeve for slidably engaging a barrel to form with the barrel a chamber, and means of preventing the rotation of the barrel during reciprocation within the supporting sleeve. 145

7. In combination, in a cannon, a cradle having a barrel supporting sleeve and a superimposed recoil cylinder supporting sleeve, a guide sleeve for said barrel rigidly mounted in the cannon supporting sleeve of the cradle, a bearing 150

- 70 sleeve on each end of said guide sleeve for slidably engaging a barrel to form with the barrel a chamber, means of preventing the rotation during reciprocation of the barrel within the supporting sleeve, a recoil cylinder mounted in the recoil supporting cylinder sleeve, means supported independent of the recoil cylinder sleeve to prevent longitudinal movement of said recoil cylinder, recoil mechanism therein, and means connected with said mechanism connected to the barrel for travel together. 80
- 75 8. In combination, a support, a relatively heavy cradle having supporting sleeve for a cannon barrel and recoil mechanism, a relatively thin guide sleeve carried in said cradle for supporting a cannon at widely spaced points exceeding the width of the cradle sleeve to support the cannon, and a recoil cylinder of relatively light material mounted in a relatively heavy sleeve of the cradle, and means interconnecting the recoil mechanism in the cylinder with the cannon barrel. 85
- 80 9. In combination, a cradle having a cannon supporting sleeve, and a recoil cylinder sleeve, a cannon guiding sleeve mounted in the first mentioned sleeve having a restricted throat at the forward end, cannon engaging sealing rings at either end, and means in one of said rings engaging in the cannon to prevent its rotation. 90
- 85 10. In a recoil mechanism, a recoil cylinder, a piston rod and a piston having an outer series and an inner series of ports, a spring-loaded valve adapted to cover one series of ports on one side of the piston and a recoil spring on the other side of the piston, a supplementary cylinder in said recoil cylinder having ports and a supplementary piston on said piston rod adapted to enter therein to cushion the movement of the piston rod at the extreme limit of its stroke in one direction. 95
- 90 11. In a recoil mechanism, a gun barrel, a main recoil cylinder stationarily held with respect to said barrel, a recoil piston rod operating in the recoil cylinder and having one end connected to said gun barrel to move with it, an intermediate auxiliary piston on said piston rod, a rearwardly disposed restricted cylinder having relief ports for receiving said piston and piston rod at the rear end of the recoil cylinder, a main piston on the forward end of said piston rod and a recoil spring interposed between the rear side of the main piston and the forward side of the rear end of the recoil cylinder. 100
- 95 12. In a recoil mechanism, a gun barrel, a main recoil cylinder stationarily held with respect to said barrel, a recoil piston rod operating in the recoil cylinder and having one end connected to said gun barrel to move with it, an intermediate auxiliary piston on said piston rod, a rearwardly disposed restricted cylinder having relief ports for receiving said piston and piston rod at the rear end of the recoil cylinder, a main piston on the forward end of said piston rod and a recoil spring interposed between the rear side of the main piston and the forward side of the rear end of the recoil cylinder, a supplementary restricted cylinder formed in the forward end of the recoil casing, a supplementary piston mounted on the forward end of the recoil piston rod for snuffing the final return of the barrel to battery. 105
- 100 13. In a recoil mechanism, a gun barrel, a main recoil cylinder stationarily held with respect to said barrel, a recoil piston rod operating in the recoil cylinder and having one end connected to said gun barrel to move with it, an intermediate auxiliary piston on said piston rod, a rearwardly disposed restricted cylinder having relief ports for receiving said piston and piston rod at the rear end of the recoil cylinder, a main piston on the forward end of said piston rod and a recoil spring interposed between the rear side of the main piston and the forward side of the rear end of the recoil cylinder, a supplementary piston mounted on the forward end of the recoil piston rod for snuffing the final return of the barrel to battery, and a yieldingly mounted valve member adapted to control ports in the main piston, said valve member being located between the last mentioned supplementary piston and the main piston. 110
- 105 14. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, and a yielding means between the rear end of the recoil casing and the main piston. 115
- 110 15. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston. 120
- 115 16. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston, said main piston having ports therethrough, and means for yieldingly covering a portion of said ports located between the forward supplementary piston and the forward side of the main piston. 125
- 120 17. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston, said main piston having ports therethrough, and means for yieldingly covering a portion of said ports located between the forward supplementary piston and the forward side of the main piston. 130
- 125 18. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston, said main piston having ports therethrough, and means for yieldingly covering a portion of said ports located between the forward supplementary piston and the forward side of the main piston. 135
- 130 19. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston, said main piston having ports therethrough, and means for yieldingly covering a portion of said ports located between the forward supplementary piston and the forward side of the main piston. 140
- 135 20. In a recoil mechanism, a pair of spaced tubular supports, one of which permits the slidable movement of a gun barrel therein and the other of which prevents the movement of a recoil casing therein, a gun barrel, a recoil casing so mounted, a recoil piston rod reciprocable in said recoil casing but connected at its rear end to said gun barrel, an intermediate auxiliary piston on the center of said piston rod, a main piston adjacent the forward end of the said piston rod and a supplementary piston near the forward end of said piston rod, a restricted head for said recoil casing to form a supplementary cylinder for the last mentioned piston on the forward end of the piston rod and a second supplementary cylinder of restricted area at the rear end of the recoil casing having ports, said last mentioned cylinder being adapted to receive the intermediate piston on the piston rod, a yielding means between the rear end of the recoil casing and the main piston, said main piston having ports therethrough, and means for yieldingly covering a portion of said ports located between the forward supplementary piston and the forward side of the main piston. 145

LOUIS L. DRIGGS, JR.
